UNITED STATES PATENT OFFICE.

CHARLES H. WIDMAN, OF DETROIT, MICHIGAN.

AUTOMOBILE BODY AND METHOD OF MANUFACTURING THE SAME.

Application filed February 20, 1923. Serial No. 620,137.

To all whom it may concern:

Be it known that I, CHARLES H. WIDMAN, a citizen of the United States of America, residing at Detroit, in the county of Wayne and State of Michigan, have invented certain new and useful Improvements in Automobile Bodies and Methods of Manufacturing the Same, of which the following is a specification, reference being had therein to the accompanying drawings.

This invention relates to vehicles and refers more particularly to the bodies thereof.

An object of the invention is to simplify and to expedite the process of manufacturing vehicle bodies, while at the same time to obtain an improved construction.

Another object is to provide a construction in which the separate panels or elements of the body are enameled before assembly, so as to simplify the assembly of the parts, making possible their attachment without marring the outer portions thereof, and at the same time permit the removing thereof in case any of them may become damaged and the substitution of like undamaged parts.

Another object is to provide simple and effective means for securing the panels to the frame of the body and for concealing the securing means as well as the crevices between the assembled panels, whereby the various parts after being enameled may be so suspended for drying that the edges from which the enamel drips will be the edges which are concealed from view.

With the above and other objects in view the invention consists of certain novel features of construction, combination and arrangement of parts as will be more fully described and particularly pointed out in the appended claims.

In the accompanying drawings:

Figure 1 is a side elevation of a vehicle body embodying my invention;

Figure 2 is a front elevation thereof;

Figure 3 is a perspective view of the vehicle body frame;

Figure 4 is a vertical sectional view through the rear end of the body;

Figure 5 is a sectional view taken on line 5-5 of Figure 1;

Figure 6 is a sectional view taken on line 6-6 of Figure 1;

Figure 7 is a fragmentary horizontal sectional view through the rear end of the body;

Figures 8, 9 and 10 respectively are fragmentary sectional views of slightly modified

constructions, showing the joining of cloth panels with metal ones.

In the present state of the art, bodies for motor vehicles are usually formed of metal panels mounted on a frame which is constructed of either metal or wood. Where wooden frames are used the drying of the paint or enamel must be effected at comparatively low temperatures as otherwise the frames will be injured. On the other hand where metal frames are used, the enamel may be subjected to relatively high temperatures, resulting in a finish which is improved both in appearance and in durability. However, the assembled body on account of its size and weight is inconvenient to handle and occupies a great deal of valuable space in the finishing ovens.

With the present invention, I combine a baked enamel finish with a wooden frame construction and I also simplify the enameling process by enameling the separate panels or elements of the body before assembly.

Referring now to the drawings in which like characters of reference designate corresponding parts throughout the several views, the numeral 1 designates a vehicle body having a frame 2 which is preferably constructed of wood and which is preferably of the construction illustrated in Figure 3. As shown in this figure, the frame is composed of the sill members 3, post members 4, a top 5 and the other usual elements of such a structure.

A plurality of metallic panels 6 overlie the frame as illustrated in Figure 1 and form the finished exterior of the body. These panels are preferably enameled before they are assembled and are preferably provided at their margins with a series of apertures 7 which receive the nails, screws or other devices 8 for securing the panels to the frame. The adjacent edges of the panels are not joined directly to each other and to conceal the crevices therebetween and the securing devices, suitable finishing strips of molding 9 are used. Each strip of molding 9 is preferably constructed of metal and is secured in position over the crevices between the panels 6 by means of the bolts 10 and nuts 11. The heads 12 of the bolts are preferably located between the transversely curved outer surface 13 and the spaced flat inner surfaces 14 of the molding, while the shanks 15 of the bolts extend through the wood-work of the frame and are engaged by the

nuts 11. These nuts are preferably located in recesses 16 in the woodwork of the frame 2 and may be adjusted upon the shanks of the bolts to clamp the flat portions 14 of the molding between the heads of the bolts and the panels 6 upon opposite sides of the joint. The shanks 15 of the bolts are preferably provided adjacent to their heads with square portions 17 which are disposed between the adjacent edges of the flat portions 14 so that the bolts will be prevented from turning when the nuts are adjusted.

The doors 18 of the body are also preferably provided with enameled metallic panels 19 which overlie wooden frames 20, and the crevices between the panels 19 and the strips 21, which are provided adjacent to the windows, are preferably concealed by means of molding 22 which is preferably similar in construction to the molding 9. The doors may be pivotally mounted in any suitable manner upon the frame of the body and are preferably provided at their free edges with strips of molding 23 which conceal the securing elements 24 and which are adapted to abut and overlap the adjacent panels 6 on the frame of the body when the doors are closed. As shown in Figure 7 the strips 23 are preferably T-shape in cross-section and the webs 25 thereof are preferably secured by means of nails 26 to the frames 20 of the doors.

If desired, a slightly different form of molding may be used to conceal the securing elements and the crevices between the enameled panels of either the body or the doors. As shown in Figure 8, solid strips of molding 27, having transversely curved inner and outer surfaces 28 and 29 respectively, are secured in position over the adjacent ends of the panels 6 and conceal the securing elements 30 and the crevices between the panels. This form of molding may also be used at the rear of the body to conceal the joints between the side and back panels as illustrated in Figure 7.

The entire exterior finish of the body may be constructed of metal panels, but portions of this finish are preferably formed of fabric. Thus, as shown in Figure 9, an enameled metallic panel 31 is adjacent to a fabric panel or covering 32 and in addition to a metallic strip of molding 33, which is preferably constructed similar to the molding 27 and which is preferably secured to the metal panel 31 adjacent to the fabric covering 32, an adjoining supplemental strip of molding 34 is secured to the fabric covering 32. The molding 34 is preferably constructed of fabric which is preferably folded around suitable reinforcing elements such as a rod 35 and a strip 36 which may be formed of any suitable material. The nails 37 used to secure the fabric covering 32 to the frame of the body are preferably driven

through the two inner plies 38 of the molding 34, and the reinforcing strip 36 and fabric covering therefor are then secured by any suitable means to the plies so as to conceal the heads of the nails.

70

In Figure 10, I have shown a fabric panel or covering 40 secured to the frame of the body and an adjoining enameled panel 41 which forms the cowl of the vehicle. A strip of molding 42 corresponding to the strip of molding 34 is preferably used to conceal the securing elements 43 and the crevices between the fabric covering 40 and the metal panel 41.

75

While it is believed that from the foregoing description, the nature and advantages of the invention will be readily apparent, I desire to have it understood that I do not limit myself to what is herein shown and described and that such changes may be resorted to when desired as fall within the scope of what is claimed.

80

What I claim as my invention is:

1. The method of manufacturing an automobile body which consists in first forming a plurality of panels and strips and a cowl so as to provide some of them with bent edges and some with bends intermediate their edges to form corner portions, then enameling said panels, strips and cowl and then assembling them to a wooden body frame with said bent edges turned over portions of the frame.

85

2. The method of manufacturing an automobile body which consists in first forming a plurality of panels and strips and a cowl so as to provide some of them with bent edges and some with bends intermediate their edges to form corner portions, then enameling said panels, strips and cowl and then removably securing them by separate securing means to a wooden body frame with said bent edges turned over portions of the frame, to form an outer shell of separably removable and separately applied parts.

90

3. An automobile body comprising a wooden frame and a plurality of pre-formed panels, strips and a cowl, some of which have bent edges and some bent portions intermediate their edges to form corner portions, all of which have been provided with a finishing coating before assembly to the frame and after being formed, and means for securing said panels, strips and cowl to said frame with said bent edges turned over portions of said frame.

95

4. An automobile body comprising a wooden frame and a plurality of pre-formed panels, strips and a cowl, some of which have bent edges and some bent portions intermediate their edges to form corner portions, all of which have been provided with a finishing coating before assembly to the frame and after being formed, and means

100

105

110

115

120

125

130

for removably securing said panels, strips and cowl to said frame by individual securing means.

5. An automobile body comprising a wooden frame and a plurality of pre-formed and pre-enamed panels, strips and a cowl, removably and separately secured directly to said frame, some of said pre-formed panels and strips being secured to form door and window openings and having pre-formed bent edges secured over portions of said frame, hidden from exterior view.

6. An automobile body comprising a wooden frame and a plurality of pre-formed parts forming a casing for said frame, some of which parts have bent edges and some bent portions intermediate their edges to form corner portions, which parts have been provided with a finishing coating before assembly to the frame and after being formed, and means for securing said parts to said frame with said bent edges turned over portions of said frame.

7. An automobile body comprising a wooden frame and a plurality of pre-formed parts forming a casing for said frame, some of which parts have bent edges and some bent portions intermediate their edges to form corner portions, which parts have been

provided with a finishing coating before assembly to the frame and after being formed and means for removably securing said parts to said frame by individual securing means.

8. An automobile body comprising a wooden frame and a plurality of pre-formed parts forming a casing for said frame, some of which parts have bent edges and some bent portions intermediate their edges to form corner portions, which parts have been provided with a protective coating before assembly to the frame and after being formed, and means for securing said parts to said frame with said bent edges turned over portions of said frame.

9. An automobile body comprising a wooden frame and a plurality of pre-formed parts forming a casing for said frame, some of which parts have bent edges and some bent portions intermediate their edges to form corner portions, which parts have been provided with a protective coating before assembly to the frame and after being formed, and means for removably securing said parts to said frame by individual securing means.

In testimony whereof I affix my signature.

CHARLES H. WIDMAN.
